UNITED STATES PATENT OFFICE.

EDWARD ALBRECHT, OF PHILADELPHIA, PENNSYLVANIA.

SLED.

1,355,520.

Specification of Letters Patent.

Patented Oct. 12, 1920.

Application filed December 7, 1918. Serial No. 265,682.

To all whom it may concern:

Be it known that I, EDWARD ALBRECHT, a citizen of the United States, residing in the city and county of Philadelphia, State 5 of Pennsylvania, have invented a new and useful Sled, of which the following is a specification.

My present invention consists of a novel construction and arrangement of a sled 10 wherein mechanism is provided for enabling one to mechanically effect the forward movement of a sled.

It further consists of a novel construction of a sled having fulcrumed in it a lever 15 which is provided with cutting or gripping members, and the lever has connected with it one or more springs, each of which preferably has a pulling strength of twice the weight of one person, and move the lever 20 in such a direction that the sled is moved forwardly.

It further consists of a novel construction and arrangement of a lever, a novel construction and arrangement of a cutter 25 and novel means for connecting the cutter and its holding devices with respect to the lever.

It further consists of a novel construction and arrangement of sled steering mechanism.

It further consists of other novel features of construction and advantage which will hereinafter more clearly appear in the detailed description of my invention.

For the purpose of illustrating my invention, I have shown in the accompanying drawing a preferred embodiment of it which in practice will give satisfactory and reliable results. It is, however, to be understood that this embodiment is typical only and that the various instrumentalities of which my invention consists are capable of being variously arranged and organized and that the invention is not limited to the precise arrangement and organization of these instrumentalities as herein set forth.

Figure 1 represents, in side elevation, a sled embodying my invention.

Fig. 2 represents the sled in end elevation with the seat removed and with a portion of it broken away to more clearly show the construction.

Fig. 3 represents, on an enlarged scale, and in side elevation, a cutter and certain of its adjuncts.

55

Similar numerals of reference indicate corresponding parts.

Referring to the drawings.

1 designates the side members of a sled embodying my invention said sides having 60 secured to them in any desired manner a top 2. The sides have connected to their bottom the runners 3 which are preferably integral with the sides as shown. The sides are of skeleton formation and would preferably be formed from metal such as sheet 65 steel or a casting.

The sides are provided with the cam grooves 4 into which extends a rod 5 which is connected to and passes through the bifurcated ends of a lever 6 which extends upwardly through the top and is provided with trunnions 7 which are journaled in a bearing 8 secured to the sled in any desired manner.

75

9 designates a handle which telescopes into the lever 6 and is provided with fastening devices 10 whereby it can be fixed in its adjusted position. By such construction the effective length of the handle may be 80 varied so that it can be adjusted for different sized persons. The handle 9 at its upper end is preferably provided with a cross bar, as shown. 11 designates a blade holder or socket which is hinged at 12 to an end 85 of the lever 6. The sockets 11 on the opposite side of the hinge are cut away or beveled as at 13, and the lower ends of the lever 6 are also faced off or beveled as at 14, in order to facilitate the action of the 90 springs 15. One end of each spring is fixed to an end of the lever 6 and the other end is fixed to the socket 11. Each socket 11 is recessed or apertured to receive a cutter 95 blade 16 which is secured in assembled position by means of a set screw 17. Each cutter is preferably constructed of flat bar stock and is provided with a centrally located wedge-shaped tooth 18 and with side teeth 19 and 20 which flare outwardly and 100 have their lower ends terminating above the bottom of the tooth 18. In order to effect the rearward or operative stroke of the lever 6, I provide one or more springs 21. One

end of a spring is connected to the rod 5 while its opposite end is connected to an arm 22 connected to the sides 1.

In order to effect the steering of the sled, 5 I provide at each side a spring controlled lever 23 which is fulcrumed to the sides at 24 and provided at its lower end with a steering member 25 which, for purposes of illustration, I have shown as consisting of a toothed 10 wheel.

The top of the sled is provided with a seat 26 of any desired character and at the forward end is a foot-rest 27.

In the operation of my novel sled the operator 15 pulls backwardly on the handle 9 thereby placing a tension on the springs 21. During such movement owing to the pivotal connection between the cutter or socket 20 holders 11 and the lever 6 the cutters do not cut into the ground on their forward movement. The springs 21 cause the lower ends 25 of the lever to move rearwardly and, since the flattened inner end of the cutters 12 and the flattened lower ends of the lever 6 limit the relative movement of such parts in one direction, the cutting edges of the cutters will grip the ground and cause the forward 30 movement of the sled.

The sled can be steered in any desired direction 35 by the proper actuation of one or the other of the steering wheels 25 as will be apparent.

A sled constructed in accordance with my present invention is of simple and compact 35 construction and can be manufactured at a minimum cost, and the parts are constructed and arranged in such a manner that the sled is durable and is not liable to get out of order.

It will now be apparent that I have devised 40 a novel and useful construction of a sled which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible 45 of modification in various particulars without departing from the spirit or scope of the invention or sacrificing any of its advantages.

Having thus described my invention what 50 I claim as new and desire to secure by Letters Patent, is:—

1. In a sled, a fulcrumed lever, a cutter 55 movably carried by said lever and adapted to move relatively to the lever on its inoperative stroke, and a spring having a pulling

strength greater than the normal load on the sled connected to said lever and to a fixed point of the sled to effect the power stroke of the lever.

2. A sled having sides and a top, said 65 sides having cam grooves therein, a power lever pivotally connected to said sled and having means to engage said cam grooves, a cutter socket pivotally carried at the lower end of said lever and adapted to open on 70 the rearward stroke of said lever, and a spring having one end connected to said lever and its other end to a fixed portion of said sled to effect the power stroke of the lever. 75

3. A sled having sides provided with grooves, a lever fulcrumed to said sled and having means extending into said grooves, cutters pivotally supported with respect to said lever and adapted to open when the upper end of said lever is moved rearwardly, a spring to cause said cutters to close when the upper end of said lever is moved forwardly, and resilient means connected with said lever to effect such forward movement 80 of the upper end of said lever. 85

4. A sled having sides, a lever fulcrumed in said sled, a cutter socket hinged to said lever and adapted to open when the lower end of said lever moves forwardly, a spring 90 to effect the closing of said cutter socket, a cutter carried by said socket, and a spring connected with a fixed portion of said sled and with said lever to effect the rearward movement of the lower end of such lever. 95

5. A sled having sides, a lever fulcrumed in said sled and having a bifurcated end, a cutter socket hinged to each end and adapted to open when the lower end of the lever moves forwardly, springs to effect the closing of said sockets, cutters carried by said sockets, and springs having one end operatively connected with said lever and their other end connected with a fixed portion of the sled to effect the rearward movement 100 of the lower end of the lever. 105

6. A sled having sides and a top, the sides being provided with grooves, a lever journaled in said sides and having a bifurcated lower end, means to vary the effective length of said lever, cutters movably carried at the lower end of said lever, a rod extending through said lever and into said grooves, springs connected to said rod and to a fixed portion of the sled, and steering 110 means for said sled. 115

EDWARD ALBRECHT.
